UNITED STATES PATENT OFFICE.

ADA LOUISE GREENWOOD, OF NEW YORK, N. Y.

WOMAN'S GARMENT.

Specification of Letters Patent. Patented Dec. 15, 1914.

1,121,010.

Application filed February 24, 1914. Serial No. 820,455.

To all whom it may concern:

Be it known that I, ADA LOUISE GREENWOOD, a subject of the King of Great Britain, and a resident of New York city, county and State of New York, have invented certain new and useful Improvements in Women's Garments, of which the following is a specification, reference being had to the drawings herein referred to and made a part hereof.

My invention relates particularly to a simplified garment for woman's apparel, having many advantages as will hereinafter appear.

Among other objects I produce a garment suited for conditions frequently met in the atricals, for dancing or bathing, and many other activities, and for convenience of certain classes of people for general use. Where requirements call for a garment fitting close to the figure from the bust down and without any break in continuity visible through sheer skirts, my garment is particularly adapted. It constitutes in one garment a reinforced body supporting portion merging into knickers, thereby completing the garment as a covering for the person and revealing no gap above the stockings. By the embodiment of my invention such a garment is continuous from the waist down with practically no break visible through thin skirts. It may be made lighter than the several garments which it supplants, while eliminating surplus material and producing a garment completely clothing the person, with the greatest lightness and simplicity.

Other objects are to produce a garment that may be readily put on and secured as easily as the usual corset, and which will at the same time be a garment that can be laundried, for which purpose I provide means for readily removing the boning, if desired. In all a garment is produced which in a unit is put on and affords the support of a corset and the protection of knickers or drawers, and while making effective a smooth unbroken line, also affords all of the conveniences essential to either of these garments.

One embodiment of my invention is shown in the accompanying drawings made a part hereof, in which:

Figure 1 is a front view of the garment on a figure; Fig. 2 is a rear view of a garment on a figure; Fig. 3 is an elevation of

the adjustable side seam; Fig. 4 is a detail of the front closure.

In the figures, A is the reinforced body supporting portion; B is the body supporting or confining continuation of the material of the upper portion; C is the lower part of the body material where formed into legs; D is the portion of lighter material forming the lower extremity; E—E are hose supporters fastened at e to C, which is the lower extremity of the same material constituting the body portion.

As indicated at A, stitching F represents the reinforced portion which may extend to the top, or not, depending upon the detail of corset design required by the individual or in fashion; G represents groin boning; H is the front boning which may be made double or single, or may be supplanted by front clasps; J—J' are the side seam boning, which, as shown, are spread apart with the material immediately adjacent sewed together; K—K is next to back boning, which preferably extends slightly beyond the reinforced portion; L is the lacing which extends from the top beyond the reinforced portion and to a practical point, drawing together the entire garment throughout the reinforced body supporting portion, as well as the hip portion in order to give it the required close fit and supporting qualities, and produce the smooth effect over the hips; M is the front flap which may be extended as far as desired, and if the front boning H is supplanted by clasps, then the fly M will merge into the clasps, but will have different character of fasteners as it is desired to close the front securely as far down as possible for all practical purposes.

As will be seen the reinforced portion F may constitute more or less of the body supporting portion A, serving however to sufficiently support the body at least slightly above and below the waist line.

The material necessary for required strength, and yet suppleness, is selected and, depending upon the individual case, the amount of boning is embodied in the reinforced portion F. The boning may extend below and above the reinforced portion, but primarily must give the required stiffness without interfering with suppleness to effect support and still leave a smooth surface as it merges into the lower portion. While I prefer two thicknesses in the portion F, the

same material of one thickness only extends downward, continuous with the portion F, carefully fitting the body and hips, thereby affording material of sufficient strength at B 5 to stand the strain of the lacing L and draw the garment tight about the body with the required support and effect. The same material continues into legs C, which may be longer or shorter, as desired in any particular case, and at the lower extremity thinner or sheer material constituting knickers, is joined to form a continuation to the legs C, to any extent desired but preferably sufficient to overlap the top of the hose. This 10 may, of course, extend above or below the knee, but the joining between the sheer material is preferably made so as not to be visible through the outer garments, which at this point are loose. For many reasons 15 the lower extremity of the garment must be of lighter and softer material than could be used for the requirements of stiffness or strength in the upper garment.

To still further simplify the apparel, I 20 attach hose supporters to the portion C, which being stiff in view of the other requirements of that part of the garment, affords the necessary strength for this hose support. These supporters E are consequently invisible and still further aid to the smooth effect of the entire garment; in addition to which they afford means to hold the garment down.

The knickers may be lengthened or shortened at will, and the relative proportion of the body supporting portion A to the body or hip portion B, and leg portion C and knicker portion D may be varied to suit individuals or taste.

40 The side seam shown in Fig. 3, affords a ready means of varying the size for more accurate fit. This is effected by joining the seam holding the two parts of the side together, whereupon the adjacent edges of the hip seam will have boning substantially from the upper to the lower extremity of the reinforced portion, but preferably extending still farther below. For adjustment, the seam is ripped and a seam run 45 from the top to the bottom as near or as far from the boning as desired, to take in or let out the garment at will. When the seam is sewed up the boning will still lie flat, though diverging more or less at the top, 50 and still in any case affording the desired support of the hip boning without producing any additional folds or thickness in the seam.

In cases such as for bathing suits, it is

entirely practical to produce the garment of 60 the same material throughout. The lower extremities of leg extensions are drawn in, and as such constitute what are usually called knickers. While these extremities are preferably stitched to the main portion or 65 constitute a continuation of its material, in certain cases I may button or otherwise detachably fasten the lower portion to the upper for obvious reasons, but as this point of attachment is well down on the leg it is 70 where the garment must be loose to permit movement, and therefore the fastenings will not show or interfere with the unbroken smooth contour of effect desired. The main object being accomplished by having a 75 smooth effect from top to bottom, while the only joint, if any, is so low as to be beyond the body fitting point, and would therefore not be visible through the outer garments. In other respects, while I have shown a preferred form of my garment, various details may be changed in the boning, lacing, reinforcing, and as to the dimensions of other parts, without departing from the spirit of 80 my invention, but

What I claim and desire to secure by Letters Patent is:

1. A one-piece woman's garment, comprising a body-supporting and hip-confining portion of comparatively heavy material, 90 boning in said body-supporting and hip-confining portions, the lower portion of said hip-confining portion being formed to encircle the legs of the wearer, and leg encircling portions formed of comparatively lighter 95 material attached to and extending from the lower edge of said hip-confining portion.

2. A one-piece woman's garment, comprising a body-supporting and hip-confining 100 portion of comparatively heavy material, boning in said body-supporting and hip-confining portions, leg encircling portions formed of comparatively lighter material attached to and extending from the lower 105 edge of said hip-confining portion, and hose supporters attached to the lower edge of the hip-confining portions and extending within the leg encircling portions.

In testimony whereof, I have signed my 110 name to this specification, in the presence of two subscribing witnesses, this 11 day of Feby 1914.

ADA LOUISE GREENWOOD.
